UNITED STATES PATENT OFFICE.

HARRY KELLER, OF CHICAGO, ILLINOIS.

RIVET BREAKER.

1,119,269.

Specification of Letters Patent. Patented June 13, 1922.

Application filed January 27, 1920. Serial No. 354,408.

To all whom it may concern:

Be it known that I, HARRY KELLER, a citizen of the United States, residing in the city of Chicago, county of Cook, State of Illinois, 5 have invented a new and useful Rivet Breaker, of which the following is a specification.

My invention consists of a novel construction of a pneumatic rivet breaker, wherein I 10 employ a cylinder having a grooved piston therein, which has a stroke considerably in excess of its own length, whereby friction is diminished, a reduction of weight is obtained and a very powerful blow can be 15 struck upon the rivet or other article to be acted upon, said cylinder having a novel arrangement of inlet and exhaust ports therein and being capable of being produced at a minimum expense and by reason of my 20 novel construction of valve end and coacting inlet and supplemental exhaust passages, I am enabled to obtain a maximum efficiency of power from the compressed air or motive fluid employed and I am also, by reason of 25 a novel arrangement of springs located at the front and rear of said cylinder enabled to reduce to a minimum the shock, jar and vibration which has heretofore been incident to the operation of tools of this general character. 30

My invention further consists of a novel construction of a controlling valve which is manually operated in a novel manner by means of a handle which is located within 35 the front and rear ends of the piston cylinder, so that said handle or valve operating means is more readily and conveniently accessible than heretofore, and is actuated in a plane parallel to the axis of said cylinder.

It further consists of a novel construction 40 of a head block, a valve located transversely therein and provided with novel inlet and outlet grooves and passages for controlling the inlet and exhaust of the compressed air or other motive fluid.

It further consists, in a device of the character stated, of a novel construction of a cylinder having a plurality of constantly open supplemental exhaust passages, in the forward end thereof, for the purpose of speeding up the hammering piston and enabling the same to strike a heavier and quicker blow than heretofore and in addition permitting a quicker return or backward movement of 55 the piston to the rear of the cylinder preparatory to striking the forward blow.

By my novel invention a rivet cutter or breaker is produced wherein the rivets may be cut quickly in about three blows of the hammering piston and which can be handled 60 conveniently and easily by a minimum number of operators and readily controlled by one of said operators.

For the purpose of illustrating my invention, I have shown in the accompanying 65 drawings one form thereof which is at present preferred by me, since the same will be found in practice to give satisfactory and reliable results, although it is to be understood that the various instrumentalities of 70 which my invention consists can be variously arranged and organized and that my invention is not limited to the precise arrangement and organization of these instrumentalities as herein shown and described. 75

Figure 1 represents a side elevation of a pneumatic rivet breaker, embodying my invention.

Figures 2 and 3 represent longitudinal sectional views of Figure 1 showing the valve, 80 its piston and coacting ports in the respective positions they may assume.

Figure 4 represents a transverse sectional view showing the valve and its head block the valve being in the exhaust position. 85

Figure 5 represents a side elevation of the valve.

Figure 6 represents a top plan view of Figure 5 and the valve stem being shown in section. 90

Figure 7 represents a perspective view of said valve.

Similar numerals of reference represent corresponding parts in the figures.

Referring to the drawings: 95

1 designates my novel construction of rivet breaker, the same comprising the cylinder or barrel 2, whose rear end is fitted into the head block or valve block 3, and whose forward end is secured within the nosepiece 100 4, whose forward extremity has threaded or otherwise secured therein the bushing 5, in which is received the shank 6 of the chisel or other working tool 7, which is applied to the rivet to be cut or broken, said shank 6 105 being surrounded by the coil spring 8, whose forward end abuts against the contiguous end of said bushing 5. The cylinder 2 is provided with the piston chamber 9 in which reciprocates the hammering piston or plunger 10, which comprises the two end heads 11 connected by the neck 12 of lesser di-

ameter whereby the piston is lightened and friction reduced. The rear end of the piston chamber 9 contains the coil spring 13, which is adapted to abut against the wall 14 of the head block and protect the latter from the impact of the piston 10 on its return or rearward stroke, as will be understood from Figure 2. The head block 3 is provided with a novel construction of valve 15, which is 5 preferably a rotary valve and is arranged in the head block transversely to the axis of the cylinder 2. The construction of this valve will be best understood from Figures 4 to 7, said valve having the stem 16 projecting therefrom at a right angle to the axis of the cylinder 2, which stem passes through the nut 17, screwed into the head block 3. The stem 16 has secured to its outer end the handle 18 provided with the 10 knob 19 for convenient manipulation, it being apparent that said valve operating handle does not lie beyond the end of the tool or its head block in a plane at right angles to the axis of the tool, but extends 15 and is movable in a plane parallel with the axis of the tool. The valve 15 is assembled within its chamber in the head block, so that a shallow spring chamber 20 is formed 20 in which I locate the spring 21, whose function is to press the valve at all times outwardly against the nut 17, whereby the requisite tight joint is obtained between the working parts and any wear on the contiguous parts is automatically taken up. 25

30 The motive fluid which is preferably compressed air enters the head block at the inlet 22, and when the parts are in the position seen in Figure 3, it will be understood that the air flows through the transverse valve port 23 of the valve and the passage 24 of the head block against the rear end of the piston 10, so that the latter is driven forwardly into the position seen in Figure 3 where said piston is shown in the act of impacting upon the shank of the chisel or other working tool. During the forward travel of the piston, there has been a free and unobstructed exhaust of the motive fluid in advance of the piston through the ports 25 40 and 26 which lead to the common exhaust passage 27 having its outlet at 28 to the atmosphere, it being evident that by the provision of the forward supplemental exhaust ports 25 and 26, which are constantly open 45 and uncontrolled by any valve, that the forward blow of the hammering piston 10 is unimpeded and unobstructed to a minimum extent, so that a very rapid and powerful forward blow is imparted to the shank 6 of the working tool. During the forward movement of the piston 10, the exhaust from the forward end of the piston takes place through the forward port 29, passage 30 and passage 31 into the grooves 32 and 33 into 50 the exhaust pipe 34 to the atmosphere, as

60

65

will be understood from Figure 4 in which the valve is shown, as exhausting from the front end of the cylinder.

The relative position of the parts during the forward movement of the piston in 70 striking a blow and the manner of exhausting from the forward end of the piston being understood from Figures 3 and 4 and the heavy blow having been struck on the shank 6 of the chisel 7, the valve 15 is next 75 manually turned from the position seen in Figures 3 and 4 into the position seen in Figure 2, whereupon the flow of motive fluid against the rear end of the piston 10 is cut off and as the piston 10 moves from the 80 position seen in Figure 3 to the position seen in Figure 2, exhaust is at once permitted through the ports 25, 27 and 28. The motive fluid now flows through the inlet 22, grooves 33 and 32, and passage 31 (see Figure 2) 85 and passage 30 and port 29 to the forward end of the cylinder 2 and the piston 10 is caused to move from the position seen in Figure 3 to the position seen in Figure 2, the remaining exhaust from the rear end of 90 piston 10 taking place through the port 24 and exhaust port 35 and port 23 of the valve 15 to the atmosphere.

The piston 10 is cushioned in its rearward strokes by its impact upon the spring 13 as 95 will be understood from Figure 2, which also serves to accelerate the forward movement of said piston which is desirable in devices of this character.

I desire to call special attention to the 100 constantly open exhaust ports 25 and 26 which are uncontrolled by any valve, since by the provision thereof particularly the forward exhaust port 26, I have found by practical tests that I am enabled to strike a 105 blow of 25% additional power, so that an ordinary rivet can be broken in about three blows of the hammering piston. The pipe containing the passage 30 instead of being a rubber hose as in certain prior constructions with which I am familiar is preferably a metal tube brazed or soldered to the cylinder 2. The movement of the valve handle 18 from its extreme positions seen in Figure 1 can be limited by pins or abutments or shoulders 36 and 37 formed on the nut 17. 110

I am aware of the patent to Sedinger No. 1,201,986, but my invention is differentiated therefrom, since my valve construction is 115 entirely dissimilar as is the valvular control of the cycle of operation and my valve operating handle does not lie beyond the head of the tool in a plane at right angles to the axis of the valve and head, but extends and is operable in a plane parallel to the axis of the cylinder, and the manner of effecting the valvular control of the inlet and exhaust of the motive fluid from the forward end of the cylinder is different 125 130

from the patent aforesaid, since my novel valve simply comprises the plug or body having the internal ports 23 and 35, and the external channels 32 and 33, which can be cheaply formed, and to none of the constructions of the prior art do I herein make my claim.

It will now be apparent that I have devised a new and useful rivet breaker which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim is new and desire to secure by Letters Patent, is:

1. A pneumatic rivet breaker, comprising a cylinder, a head block for the rear end of said cylinder and having a transverse valve seat therein, a nose piece for the forward end of said cylinder, a piston for said cylinder, cushioning springs located in the extreme ends of said cylinder, a rotary valve in said transverse valve seat, having a body provided with a diametric port, a port at right angles thereto, an annular outer air passage and an outer longitudinal channel, said cylinder and head block having ports and passages controlled by said valve for permitting the inlet and exhaust of motive fluid and means for actuating said valve operable in a plane parallel to the axis of said cylinder.

2. A pneumatic rivet breaker, comprising a cylinder, a head block for the rear end of said cylinder and having a transverse valve seat therein, a nose piece for the forward end of said cylinder, a piston in said cylinder, a rotary valve in said transverse valve seat, having a body provided with a diametric port, a port at right angles thereto, an annular outer air passage and an outer longitudinal channel, said cylinder and head block having ports and passages controlled by said valve, for permitting the inlet and exhaust of motive fluid, and a plurality of exhaust passages in the forward end of said cylinder which are constantly open to the atmosphere and uncontrolled by any valve.

3. In a pneumatic rivet breaker, a valve comprising a body portion having the port 23 extending diametrically therethrough about midway of its ends, a port 35 extending at an angle to said port 23, an air passage 32 at one end of said valve and in communication with a longitudinally extending channel 33, which terminates at

about the middle of said valve, a valve stem for said valve, an operating handle therefor, a head block having a transverse valve seat therein in which said valve is located, a cylinder, a piston, and ports and passages 70 common to said head block and to the forward end of said cylinder for effecting the reciprocation of said piston.

4. A pneumatic rivet breaker, comprising a cylinder, a head block secured thereto 75 and having a transverse valve seat therein, a nose piece also secured to said cylinder and having a tool receiving bushing therein, a spring located in said nose piece, a spring located in the rear end of said cylinder 80 85, a piston in said cylinder, and a rotary valve mounted in said transverse seat in said head block, said valve being provided with the port 23 extending diametrically through the body thereof, and the port 35 in said body extending at an angle to said port 23, said valve body also having the outer channel 32 formed therein, which communicates with a longitudinal channel 33, terminating at about the middle of said valve 90 body, said channels 32 and 33 serving alternately as inlet and exhaust passages for the motive fluid to and from the forward end of said cylinder.

5. In a pneumatic rivet breaker, a cylinder 95 having a head block with a longitudinal port therethrough secured to the rear end thereof, and a nose piece secured to the forward end thereof, a tool bushing secured to said nose piece, cushioning springs located in the 100 ends of said cylinder, a rotary valve transversely arranged in said head block, and comprising a body portion having the diametric port 23 extending therethrough and a port 35 at right angles thereto and communicating with said port 23, an annular channel 32 formed in one end of said valve, and a longitudinally extending outer channel 33 communicating therewith, a spring 105 pressing upon one end of said valve to take up wear, a port 31 leading from the valve channel 32 to a passage 30 communicating with the port 29 at the forward end of the cylinder, and means for manually operating said valve.

6. A pneumatic rivet breaker, comprising a cylinder, a head block having a transverse valve seat therein, a nose piece secured to said cylinder and having a tool receiving bushing therein, a cushioning spring located 120 in said nose piece, a cushioning spring located in the rear end of said cylinder, a piston in said cylinder, a rotary valve mounted in its transverse seat in said head block, said valve being provided with the port 23 extending diametrically through the body thereof, and the port 35 extending at an angle to said port 23, said valve having the outer channel 32 formed therein, which communicates with the longitudinal channel 125 130

- 33, said channels 32 and 33 serving alternately as inlet and exhaust passages for the motive fluid, and the exhaust ports 25 and 26 located in the forward end of said cylinder and leading to the common exhaust passage 27 and the outlet 28 to the atmosphere, said exhaust ports 25, 26 and passage 27 being constantly open to the atmosphere and uncontrolled by any valve.
- 10 7. In a pneumatic rivet breaker, a cylinder having a head block secured to the rear end thereof and a nose piece to the forward end thereof, a tool bushing secured to said nose piece, a cushioning spring located in the rear end of said cylinder, a rotary valve transversely arranged in said head block, and comprising a body portion having the diametric port 23 extending therethrough and a port 35 at right angles thereto, and communicating with said port 23, an annular channel 32 formed in one end of said valve, and a 45 longitudinally extending channel 33 communicating therewith, a spring pressing upon one end of said valve to take up wear, a port 31 leading from the valve channel 32 to a passage 30 communicating with the port 29 at the forward end of said cylinder, supplemental exhaust ports 25 and 26 located in the forward end of said cylinder and communicating with a common exhaust passage 27 having an exhaust to the atmosphere, said supplemental exhaust ports and passages being constantly open to the atmosphere and uncontrolled by any valve
- 15 and a valve handle lying within the ends of 35 the tool proper and movable in a plane parallel to the axis of said cylinder.
8. In a pneumatic rivet breaker, a cylinder having a head block with a longitudinal port therethrough secured to the rear end 40 thereof and a nose piece to the forward end thereof, a tool bushing secured to said nose piece, cushioning springs located in the ends of said cylinder, a rotary valve transversely arranged in said head block, and comprising 45 a body portion having the diametric port 23 extending therethrough and a port 35 at right angles thereto, and communicating with said port 23, an annular channel 32 formed in one end of said valve, and a 50 longitudinally extending channel 33 communicating therewith, a spring pressing upon one end of said valve to take up wear, a port 31 leading from the valve channel 32 to a passage 30 communicating with the 55 port 29 at the forward end of said cylinder, and supplemental exhaust ports 25 and 26 located in the forward end of said cylinder and communicating with a common exhaust passage 27 having an exhaust to the atmosphere, said supplemental exhaust ports and 60 passages being constantly open to the atmosphere and uncontrolled by any valve.

HARRY KELLER.
